TROLLEY-RETRIEVER.

1,168,624.

Specification of Letters Patent.

Patented Jan. 18, 1916.

Application filed May 8, 1915. Serial No. 26,733.

To all whom it may concern:

Be it known that I, Roy E. GEARHART, a citizen of the United States, residing at Maryville, in the county of Nodaway and 5 State of Missouri, have invented certain new and useful Improvements in Trolley-Retrievers, of which the following is a specification.

This invention relates to trolley retrievers 10 and is designed more especially as an improvement on an invention of the same nature on which I filed application for patent October 29, 1914, Serial Number 869,162, my object being to produce a trolley retriever 15 more efficient in operation and composed of fewer parts and of more simple, durable and compact construction than that forming the subject matter of said aforesaid application.

With this object in view the invention 20 consists in certain novel and peculiar features of construction and combinations of parts as hereinafter described and claimed; and in order that it may be fully understood reference is to be had to the accompanying 25 drawings in which:

Figure 1, is a side elevation of a trolley retriever embodying my invention. Fig. 2, is an enlarged plan view of the retriever, the trolley pole being cut away. Fig. 3, is a 30 rear view of Fig. 2. Fig. 4, is a central vertical longitudinal section of the retriever with the parts in normal position in full lines and in tripped position in dotted lines. Fig. 5, is a similar view with the parts in 35 the positions they occupy when the pole is dropped, said figure also showing the dotted line position of the parts when the pole is drawn down to effect the recocking of the trigger, preliminary to the reelevation of the 40 trolley wheel for operative engagement with the trolley wire.

Referring to the drawings in detail, 1 indicates a suitable base adapted to be secured upon the top of a car, and pivoted 45 upon said base for horizontal movement is a bracket 2 provided at its rear end with a pair of oppositely-spaced upwardly-projecting ears 3, and at its front end with an upwardly-projecting abutment 4 provided with 50 a slot 5.

6 is a trolley pole of any suitable type, equipped at its upper end with a harp 7, carrying the usual trolley wheel 8, and 9 is the customary rope, whereby the conductor of a

car manipulates the pole when necessary. 55 The pole is secured at its lower end, as shown, or in any other suitable manner, to a rock bar 10 pivoted between its ends and preferably nearer its lower than its upper end to and between the ears 3, and pivoted 60 to the lower end of said rock bar at 11 is a forwardly extending plate 12, equipped at its front end with an upwardly-projecting flange 13.

14 is a pair of parallel rods disposed at 65 opposite sides of abutment 4 and secured at their rear ends to the flange 13 of plate 12, and mounted upon and connecting the opposite ends of said rods forward of abutment 4 is a cross bar 15, the same being held in position by lock nuts 16 engaging the rods and at opposite sides of bar 15.

Arranged longitudinally of and above the bracket 2 and the plate 12 is a trigger 17, the same being provided at its rear end with 75 a longitudinal slot 18 engaging a bolt 19 carried by the upper end of the rock bar 10, the arrangement being such that the bolt 19 may play in the slot 18 without affecting the trigger. Near its front end the trigger is 80 provided with laterally projecting lugs or ears 20 through which rods 14 slidably extend, and between said rods the trigger is formed with a portion 21 which extends through slot 5 of the abutment 4 and is provided with a forwardly-facing shoulder 22 normally imposing forward pressure against the abutment at the upper end of said slot, said pressure being supplied by a pair of 85 springs 23 mounted on the rods 14 and bearing at their opposite ends against lock nuts 23a on rods 14, and the ears 20.

It will thus be seen that the pressure of 90 said springs, through the resistance afforded by the abutment, through the instrumentality of the trigger, exerts yielding pressure rearwardly on the lower end of the rock bar 10 for the purpose of holding the trolley wheel pressed upwardly against the trolley wire, it being noted that at such time the 100 bolt 19 occupies an intermediate position in the slot 18 so that the pole is free to follow variations in the height of the wire and to spring upwardly therefrom in the event the wheel leaves the same. It being likewise 105 noted that the connection of plate 12 with the rock bar 10 below the pivotal point thereof tends to press the front end of rods

14 and the corresponding end of the trigger upwardly. It will also be seen that when the trolley pole is in dropped position, bolt 10 is at the front end of slot 18, and that 5 consequently further downward movement imparted to the pole by pulling on rope 9, tends to swing the front end of the trigger upward. This rearward pull on the trigger therefore co-operates with the springs when 10 under tension, due to the pulling of the pole downward, in raising the front end of the rods and trigger.

In practice the removal of resistance to 15 upward movement of the pole through the trolley wheel leaving the wire results in the tripping of the trigger through the force of gravity, and the consequent forward movement of the trigger in slot 5 to permit the pole to drop down until the trolley wheel 20 is below the level of the cross or span wires, not shown, for supporting the trolley wire. To insure such tripping of the trigger the rock bar 10 is provided with a pair of arms 25 which extend downwardly and forwardly and are adapted when the trolley pole jumps upward from the wire to strike abutments 26. Adjustment of these abutments provides for effecting a positive tripping of the trigger at different elevations of the trolley wheel.

Assuming that the parts are in normal 35 position, as shown in Fig. 1, it will be noticed that the cross bar 15 is barely out of contact with the front extremity of the trigger. If the wheel leaves the wire the force exerted by the springs 23, which are 40 always under compression, throws the pole upward, which movement is attended by rearward movement of bar 15 until the same engages the front extremity of the trigger. The abutment of the bar against the said 45 end of the trigger under the impetus of the pole in its upward movement carries the bar and trigger imperceptibly rearward but sufficient to take the pressure of the trigger off the abutment 4, so that the trigger, together with plate 12 and the parts 50 carried thereby are free to drop downward until shoulder 22 is below the upper end of the slot 5. By the time the trigger is thus tripped the pole has attained its limit of 55 upward movement above the level of the trolley wire and starts to drop downward and in such movement it transmits forward movement to the trigger through the instrumentality of plate 12 and springs 23. 60 When it attains the dropped position shown in Fig. 5 it is resisted by the springs 23, as at such time the bolt 19 exerts a rearward pull on the trigger and the lower end of the rock bar 10 exerts a forward push on the plate 12. Because of these opposite

movements of the trigger and plate, the springs are caused to act as a cushion against further downward movement of the pole.

In the event the trigger and rods fail to drop with sufficient quickness after the trigger is tripped, the contact of the arms 24 with abutments 25 will instantly effect the tripping action, as will be readily seen by reference to Fig. 4. To re-set the pole in operative relation to the trolley wire, the conductor pulls downward on the rope. This rocks bar 10 and compresses the springs because the rocking of said bar imparts rearward sliding movement to the trigger until the shoulder 22 thereof again occupies a 70 vertical plane rearward of the abutment 4, further downward movement of the pole then through the co-operative pressure of 75 springs 23 and the pull of the cross bar on the rear end of the trigger, causing the front 80 end of the latter to snap or spring upward until the shoulder again engages the abutment above the slot therein, as shown. The 85 pole can then be eased upward in the customary manner to effect the engagement of the trolley wheel with the trolley wire, when the parts will again be in the position shown in Figs. 1 and 2.

From the above description it will be apparent that I have produced a trolley retriever embodying the features of advantage enumerated as desirable in the statement of the object of the invention, and which is susceptible of modification in form, proportion, detail construction and arrangement of parts without departing from the principle of construction involved or sacrificing any of the advantages of the appended claims.

I claim:

1. A trolley retriever comprising a bracket provided with a slotted abutment, a rock bar pivoted to the bracket rearward of the abutment, a trolley pole carried by the rock bar, a trigger having a pin and slot connection at its rear end with the rock bar above the pivotal point thereof and extending at its front end through the slot of said abutment and provided near its front end with a shoulder, means for yieldingly pressing the trigger forwardly to hold its shoulder against said abutment, and the trolley pole yieldingly elevated, and means movable rearwardly as the trolley pole swings upward; to apply rearward pressure on the trigger, to trip the shoulder thereof from engagement with the said abutment.

2. A trolley retriever comprising a bracket provided with a slotted abutment, a rock bar pivoted to the bracket rearward of the abutment, a trolley pole carried by the rock bar, a trigger having a pin and slot connection at its rear end with the rock bar above the pivotal point thereof and extending at its front end through the slot of

130

said abutment and provided near its front end with a shoulder, means for yieldingly pressing the trigger forwardly to hold its shoulder against said abutment, and the 5 trolley pole yieldingly elevated, and means whereby upward movement of the pole beyond a predetermined point shall be caused to impose downward pressure to effect depression of the front end of the trigger to 10 tripped position.

3. A trolley retriever comprising a bracket provided with a slotted abutment, a rock bar pivoted to the bracket rearward of said abutment, a trigger having a pin and 15 slot connection at its rear end with the rock bar above the pivotal point thereof and extending slidingly through the slot of the abutment and provided with a forwardly-facing shoulder, a plate pivoted to the rock 20 bar below the pivotal point of the same, rods extending rearwardly from said plate and slidingly through the trigger, springs mounted upon said rods and exerting force 25 against said plate and trigger to hold the latter with its shoulder bearing against said abutment, and a cross bar secured to said rods and adapted under slight rearward movement thereof to impose rearward pressure upon the trigger to remove the pressure 30 of the shoulder thereof from said abutment and leave the trigger free to drop downward and slide forwardly in said slot.

4. A trolley retriever comprising a bracket provided with an abutment at its 35 front end, provided with a slot, and a pair of upwardly-projecting ears at its rear end, a rock bar pivoted between its ends to said ears, a trolley pole projecting rearwardly and upwardly from the rock bar, a trigger 40 extending slidingly through the slot of the abutment and having a pin and slot connection at its rear end with the upper end of the rock bar, and provided near its front end with a forwardly facing shoulder and 45 with laterally projecting ears, a plate

pivoted at its rear end to the rock bar below the pivotal point thereof, a pair of rods extending forward from the plate and through the ears of said trigger and at opposite sides of said abutment, springs held under compression upon said rods by and between 50 said plate and said ears, and a cross bar connecting said rods and disposed normally slightly out of contact with the front extremity of the trigger. 55

5. A trolley retriever comprising a bracket provided with an abutment at its front end, provided with a slot and a pair of upwardly-projecting ears at its rear end, a rock bar pivoted between its ends to said 60 ears, a trolley pole projecting rearwardly and upwardly from the rock bar, a trigger extending slidingly through the slot of the abutment and having a pin and slot connection at its rear end with the upper end of 65 the rock bar, and provided near its front end with a forwardly facing shoulder and with laterally projecting ears, a plate pivoted at its rear end to the rock bar below the pivotal point thereof, a pair of rods extending forward from the plate and through 70 the ears of said trigger and at opposite sides of said abutment, springs held under compression upon said rods by and between said plate and said ears, a cross bar connecting 75 said rods and disposed normally slightly out of contact with the front extremity of the trigger, an adjustable abutment, and an arm, one of said elements carried by said plate and the other movable with said rock 80 bar and adapted to contact to effect positive tripping of the trigger from engagement with the abutment.

In testimony whereof, I affix my signature in the presence of two witnesses.

ROY E. GEARHART.
